UNITED STATES PATENT OFFICE.

STEPHEN F. BORKEY, OF FLINT, MICHIGAN.

METHOD OF FORMING AXLES.

1,353,987.

Specification of Letters Patent. Patented Sept. 28, 1920.

Application filed June 7, 1917. Serial No. 173,414.

To all whom it may concern:

Be it known that I, STEPHEN F. BORKEY, a citizen of the United States of America, residing at Flint, in the county of Genesee and State of Michigan, have invented certain new and useful Improvements in Methods of Forming Axles, of which the following is a specification, reference being had therein to the accompanying drawings.

10 The invention relates to the manufacture of vehicle axles and more particularly to front axles or construction designed for the mounting of steering-wheel spindles at opposite ends thereof. Such axles are usually 15 formed by a process in which the opposite ends are successively re-fashioned by drop-forging. It is important that the axles should be of exact length, but it is difficult to secure such accuracy where the fashioning of the ends is in successive operations. 20 I have therefore devised a method and apparatus for securing absolute uniformity in length as hereinafter set forth and described. Another feature of the invention is the 25 means for re-fashioning the spring-pads of the axle simultaneously with the operation for securing accuracy in length.

In the drawings:

Figure 1 is a plan view of the machine 30 for operating upon the axle;

Fig. 2 is a side elevation thereof partly in section; and

Fig. 3 is an end elevation.

Axes of the character described usually 35 are formed with a central section A, which is of an I-beam or other structural shape. At opposite ends of this central beam section are bifurcated portions B and B' which form the bearings for the axle spindles, and 40 spring-pads C and C' are formed on the upper face of the beam adjacent to the bifurcated ends thereof. Broadly described, my improved method comprises the fashioning of the opposite ends of the axle to the desired 45 form without attempting to secure exact uniformity in length, but with the central beam portion shorter than in the finished product. The structure thus formed is then subjected to a stretching operation, 50 the fashioned end portions being brought into exact relative positions and the central portion being stretched as required.

In forging the bifurcated end portions of the axle, the spring-pads are simultaneously

fashioned, but for convenience they are 55 made symmetrical on opposite sides of the axle beam. This is not, however, the shape which is desired in the finished product, as the pad should be tilted with respect to the central plane of the beam and given a 60 slightly concave form on its upper face, which shape would be difficult to form by the drop-forging process. I therefore provide means for re-fashioning the same and imparting thereto the desired contour at the 65 same time that the axle beam is stretched.

While the method may be carried out with various constructions of apparatus I preferably employ the construction shown, which is as follows: A' is the bed of a press 70 which has mounted thereon the revoluble shaft B² carrying cranks C² connected by pitman-rods D with a sliding cross-head E. F is a work-holder extending transversely of the bed and bearing against an abutment 75 G thereon which is opposed to the movement of the sliding head E. This work-holder includes a stationary, transversely-extending guide and a pair of clamping heads H slidable upon said guide and engageable with the axle. As specifically 80 shown, these clamping heads have upper and lower die-members I and J for embracing the beam adjacent to the pads, a clamping-lever K having a cam L for bearing on 85 the upper die and a hinged or pivoted member M for said lever and cam rockable to a position permitting the engagement and disengagement of the work, and in operating position connected to the lower die-member 90 by a link N. The arrangement is such that the axle may be engaged with the upper and lower die-members I and J when the lever K is in the position K', Fig. 2, and by then rocking said lever and mounting M to 95 the position shown at K² the link N may be engaged with a pin L', coupling the same to the lower die-member. The lever K may then be rocked upon its mounting M so as to cause the cam L to clamp the upper die- 100 member I upon the work.

Each of the clamping heads H is preferably provided with an anti-friction roll O, which is in the path of a cam member P carried by the sliding head E. This cam 105 member P has a tapering end portion P' for passing between the rolls O and for then forcing them in opposite directions, thereby

effecting a sliding movement of the heads H. As these heads when clamped to the roll are adjacent to the spring-pads C and C', the latter will act as stops or shoulders, and therefore as soon as these shoulders contact with the heads H any further movement of said heads must necessarily stretch the axle. 5

The cam P is preferably bifurcated, the 10 furcations thereof passing above and below the axle and engaging with pairs of rolls O so as to exert a stretching force symmetrically with respect to the longitudinal axis of the axle. On opposite sides of the cams P are forming dies Q which contact with 15 the pads C and C' simultaneously with or immediately succeeding the stretching operation. These forming dies, as shown are of a shape to re-fashion the axle pads, imparting thereto the desired tilt and concavity. 20

In operation, the axles which have been first formed of variable length between the opposite end portions thereof are brought to size by heating to the proper temperature 25 and then placing in the machine, as has been described. When motion is imparted to the cross-head through the medium of the pitman D and crank C² the bifurcated cams P will first engage the rolls O and force the 30 clamping heads H upon the transverse guide F in opposite directions. These clamping heads will slide upon the axle until the shoulders formed by the pads C and C' come into contact with the coöperating bearings 35 on the clamps, after which the axle is stretched until the clamps are forced to the limits of their respective movements. It will be understood that the pads C and C' are always in exactly predetermined relation 40 to the bifurcated ends of the axle, as they are formed in the same operation and by the same dies. Consequently, whatever the original length of the axle may be, after this stretching operation there will be an 45 exact dimension between the bifurcated ends; also the pads will be re-fashioned to the proper contour.

What I claim as my invention is:

1. The method of forming axles, comprising 50 the successive fashioning of opposite end portions thereof with an intermediate portion of less than the required length, and subsequently stretching the intermediate portion to secure an exact dimension between the fashioned ends. 55

2. The method of forming axles, comprising 60 the fashioning of the end portions thereof successively to exact form, said fashioned end portions including the spring-pads and the portions intermediate the fashioned ends being of less than the required length, subsequently stretching the intermediate portion to secure an exact dimension 65 between the pads, and re-fashioning said pads to the desired contour.

3. The method of forming axles, comprising the drop-forging of opposite end portions thereof to impart thereto an exact form, the portion intermediate said ends being of less than the required length, and 70 subsequently stretching the intermediate portion by means engaging the exactly-formed portion, whereby an exact dimension is secured between the ends of the latter.

4. The method of forming axles, comprising 75 the drop-forging of the opposite end portions thereof to form bifurcated spindle bearings and axle-pads, the portions intermediate said drop-forged portions being of less than the required length, subsequently 80 stretching the intermediate portion by the spreading of means engaging the exactly-formed portions, and re-fashioning the pads.

5. The method of forming axles, comprising 85 the fashioning thereof with an intermediate portion of less than the required length and the subsequent stretching of said intermediate portion to secure an exact length thereof.

6. That improvement in the art of forming 90 axles, which consists in forging the end portions thereof to exact length, holding said end portions against angular movement in respect to each other, and stretching only that portion of said axle between said end 95 portions to an accurate dimension while the end portions are so held.

7. That improvement in the art of forming 100 axles having divided end portions, which consists in forging the end portions to exact length with the intermediate portion different from the desired length, thereafter re-heating the axle and applying force to said end portions to move one in respect to the other to establish the desired exact distance 105 therebetween and an accurate alinement of one end portion with the other.

8. That improvement in the art of forming 110 axles having spring pads and divided end portions, which consists in forging the end portions and the spring pads to accurate dimensions, measured lengthwise of the axle, with the intermediate portion slightly shorter than the desired length, re-heating the axle, and stretching the heated axle 115 while the end portions are held in proper alinement one with the other.

9. That improvement in the art of forming 120 axles having spring pads and divided end portions, which consists in forging the end portions and the spring pads, to accurate dimensions, measured length-wise of the axle, with the intermediate portion slightly shorter than the desired length, re-heating the axle, stretching the heated axle while 125 the end portions are held in proper alinement one with the other, and re-forging the spring pads while the axle is still hot.

10. That improvement in the art of forming 130 axles having spring pads and divided

end portions, which consists in forging the end portions and the spring pads to accurate dimensions, measured length-wise of the axle, with the intermediate portion 5 slightly shorter than the desired length, reheating the axle, bending the end portions of the hot axle accurately into alignment with each other and maintaining them in

said relation, stretching the heated axle and re-forging the spring pads. 10

In testimony whereof I affix my signature in presence of two witnesses.

STEPHEN F. BORKEY.
